Rueger, Brooklyn, N. Y.

Application April 22, 1932, Serial No. 606,846

5 Claims. (Cl. 206—42)

This invention relates to boxes or containers adapted to hold commodities such as pills, tablets, coffee or sugar and the like.

The principal object of the invention is the production of a box of simple construction provided with an opening through which the contents of the box may be removed without the necessity of removing a cover member, said opening being opened or closed as desired by means of a slideable closure member mounted on a track member on or within the box.

Other and further objects and advantages of the invention will appear from the subjoined description taken in connection with the accompanying drawings in which:

Fig. 1 is a plan view of a box made in accordance with our invention.

Fig. 2 is a horizontal section on the line 2—2 of Fig. 1.

Fig. 3 is a cross-section on the line 3—3 of Fig. 1.

Fig. 4 is a plan view of a modification.

Fig. 5 is a horizontal section on the line 5—5 of Fig. 4.

Fig. 6 is a cross-section on the line 6—6 of Fig. 4.

Fig. 7 is a plan view of a further modification.

Fig. 8 is a horizontal section on the line 8—8 of Fig. 7.

Fig. 9 is a plan view of another modification.

Fig. 10 is a section on the line 10—10 of Fig. 9.

Fig. 11 is a plan view of another modification.

Fig. 12 is a horizontal section on the line 12—12 of Fig. 11.

Fig. 13 is a section through the upper portion of a box showing another modification.

Fig. 14 is a plan view of still another modification.

Fig. 15 is a horizontal section on the line 15—15 of Fig. 14.

Fig. 16 is a plan view of a further modification.

Fig. 17 is a section on the line 17—17 of Fig. 16.

Fig. 18 is a section on the line 18—18 of Fig. 16.

10 indicates the box body which is provided

45 with the upstanding flanges 11. The box cover is indicated at 12 and it is provided with the usual depending flanges 13 adapted to frictionally engage the flanges 11. The side walls or flanges of the box body for a certain distance of their length are preferably pressed outwardly from the normal plane of the walls as at 14 to form pockets for a purpose to be presently described. The cover 12 is provided with a slot 15 and with an annular opening 16 adjacent a corner thereof as well as with

50 a downwardly projecting lug 17. The flanges 11

of the box body are also provided with inwardly extending lugs 18 positioned as illustrated in the drawings.

19 indicates a slideable closure plate provided with downwardly extending flanges 20 adapted to interfit and be protectively mounted within as well as to slidably engage within the pressed out portions 14, said pressed out portions or pockets 14 forming track members therefor. The closure plate has an upwardly extending pin 21 which forms a finger piece and which extends through the slot 15 and it is also provided with a depression 22 for receiving the lug 17 on the box cover, the two members 22 and 17 forming a detachable lock to hold the closure plate 19 in 15 closed position whereby the opening 16 will be closed as illustrated in Fig. 1.

When the parts as described are assembled together the cover is held to the box body by a tight frictional engagement or it may be clinched over 20 or otherwise fastened to said body in any manner, it being understood that it is unnecessary to remove said cover to obtain access to the contents of the box. When access is desired, pressure is applied against the finger piece 21 whereupon 25 the lug 17 will snap out of the depression 22 and the closure plate 19 may then be slid to open position on the track members 14 just described in order to uncover the opening 16. When the cover plate 19 is slid into closed position the lug 17 automatically snaps within the depression 22 to detachably lock the closure plate in closed position. If the contents of the box are to be pills or tablets the lugs 18 have been provided to prevent the pill or tablet to be removed from lying 30 in the corner of the box and to make it assume 35 a position in alignment with the opening 16.

In the modification illustrated in Figs. 4 to 6 inclusive, the track members are formed by pressing the metal of the box body inwardly as at 23 40 instead of outwardly as in the preferred form of the invention, otherwise the operation of the parts is the same as in the preferred form of the invention.

45 In the modification illustrated in Figs. 7 and 8 the track member is formed by pressing a bead 24 inwardly from the box body and on which the flanges of the closure member ride. Also in said modification we have shown a positioning piece 25 on or fastened to the box body in any manner and which performs the same function as the inwardly pressed lugs 18 in the preferred form of the invention.

50 In the modification illustrated in Figs. 9 and 10 a round box is shown and the track member 55

which is indicated at 25 is formed by an inwardly pressed bead on the body of the box, the cover being provided with an arcuate slot 26 performing the same function as the slot 15 in the preferred form of the invention. The rotatable closure plate in this case is indicated at 27 and is of the configuration illustrated and it is adapted to open and close the opening 28 in the cover member, it being provided with a finger piece 29 adapted to ride in the arcuate slot 26.

10 In the modification illustrated in Figs. 11 and 12 the upper edge of the body member is provided with a bead 30 which itself constitutes the track member and on which the closure member rides.

15 In the modification illustrated in Fig. 13 the upper edge of the box body is flanged as at 31 and said flange constitutes the track member for the closure member.

20 In the modification illustrated in Figs. 14 and 15 a portion only of the upper edges of the opposite side walls of the box body are flanged over as at 32, said flanges constituting the track members for the closure member.

25 In the modification illustrated in Figs. 16 and 18 inclusive we have shown a round box which could be a box for coffee or the like and which is provided with a beaded upper edge as at 33 constituting the track member for a rotatable closure plate 34 adapted to open or close an opening 35 in the cover member, said cover member being also provided with an arcuate slot 36 exposing a depression 37 in the closure member and constituting a grip for the finger whereby the closure member may be rotated on the track member. The closure member is also provided with an opening 38 adapted to register with the opening 35 in the cover member. When assembling the parts we propose to employ a transparent or translucent dustproof sheet of material indicated at 39 which is interposed between the body member and the downwardly extending flange on the cover member whereby the contents of the box will be kept fresh and free from dust while permitting the contents to be inspected by rotation of the closure member to bring the openings 35 and 38 into registry. When it is desired to use the contents this may be done by simply fracturing or tearing said dustproof material at the place where said openings 35 and 38 register and then pour the contents from the container of the amount desired. The closure member is also preferably provided with shoulders 40 slidably interfitting with shouldered guiding portions 41 on the cover member and as illustrated.

55 In all the modifications we may employ if desired, a lug for the cover member and a depression for the closure member similar to the elements 17 and 22 respectively in the preferred form of the invention and constituting a detachable lock. Likewise it is to be noted that in all structures herein illustrated, we have provided an engagement between the box body and cover which fulfills the definition of having contact peripherally between those parts, and at least, a peripheral contact within some part of each quadrant when the box is considered divided by any two perpendicular diameters or lines passing through a centerpoint of the box. Furthermore, in all instances employing a flange on the closure member, the longitudinal edge of the flange rides upon the part forming the track so that the closure member is supported through the agency of both the flange and track. In each instance, again, there is provided an off-set from

the otherwise normal shape or plane of the wall, such that both a track is formed and clearance provided for free operation of the closure member. By specifying "free operation" however, we do not exclude such friction as is desired or necessary to hold the cover where slid by a positive operation by the user.

We claim:

1. A box comprising a cover member and a body member interfitting with each other and each having a side wall a part of the face whereof lies contiguous to the corresponding part of the face of the other, one of said members having an opening, and one of said side walls for a part less than its length being offset from the other side wall and forming a track between said faces of length less than the length of the side walls, and a closure member having a flange in said track and of less length than and slidable in said track to open and close said opening and having means accessible from the top of said box for actuating said closure member, said closure member lying at all times within said box irrespective of whether said opening is opened or closed.

2. A box comprising a cover member and a body member interfitting with each other and each having a side wall a part of the face whereof lies contiguous to the corresponding part of the face of the other, said cover member being provided with an opening and a slot in the upper wall thereof, and one of said side walls for a part less than its length being offset from the other side wall and forming a track between said faces of length less than the length of the side walls, and a closure member having a flange in said track and of less length than and slidable in said track to open and close said opening, and having means accessible through said slot for actuating said closure member, said closure member lying at all times within said box irrespective of whether said opening is opened or closed.

3. A box comprising a cover member and a body member interfitting with each other and each having a side wall a part of the face next the ends whereof lies contiguous to the corresponding end portions of the face of the other wall, one of said members having an opening, and one of said side walls for a mid-part thereof between the said end parts being offset from the other side wall and forming a track between said faces of length less than the length of the side walls, and a closure member having a flange in said track and of less length than and slidable in said track to open and close said opening and having means accessible from the top of said box for actuating said closure member, said closure member lying at all times within said box irrespective of whether said opening is opened or closed.

4. A box comprising a body member having side walls and a flanged cover member tightly engaging said side walls of the body member and having an opening in one of said members, a track member on said body member comprising a pocket lying outside the normal plane of a side wall of said body member and pressed from the metal of said wall and a closure member having a flange slidably in said pocket and protectively mounted therein said closure member being adapted to open or close said opening and said closure member being positioned at all times within said box irrespective of its position.

5. A box comprising a cover member and a body member interfitting with each other and each having a side wall a part of the face whereof lies contiguous to the corresponding part of the face of the other, said cover member being provided with an opening and a slot in the upper wall thereof, and one of said side walls for a part less than its length being offset from the other side wall and forming a track of a length less than the

length of the side walls and a closure member slideable on said track to open and close said opening, and having means accessible through said slot for actuating said closure member, said closure member lying at all times within said box irrespective of whether said opening is opened or closed. 5
